BUILDING BRICK

William Stanley Grice, London, England

Application October 13, 1938, Serial No. 234,830
In Great Britain October 13, 1937

1 Claim. (Cl. 72—37)

This invention relates to improved methods of and bricks for building walls and the like, one of the objects of the invention being to provide an improved form of rhomboidal brick which is designed to enable symmetrical laying with a desired thickness of bond and neat finishing to be achieved, where the advantages appertaining to the use of rhomboidal bricks are rendered practical for ordinary building purposes.

According to this invention, a rhomboidal brick is constructed with sides related by the expression $(2S+B)=L$ where S is the length of each short side of the brick, L is the length of the long side of the brick, and B is a required thickness of bonding at the face of the wall between any two bricks laid side by side. The angle α of the rhomboid is given by

$$\frac{S+B}{L} = \cosine \alpha$$

Thus when two bricks according to the invention are laid side by side with the predetermined thickness of bonding between them, a true rhomb will be formed and an inner corner of one brick in one side of the rhomb will coincide with an outer corner of the next brick in the opposite side of the rhomb, and accordingly in a course of these bricks laid as "headers" each bonding joint on each face of the course will be in line with a joint on the opposite face of the course. The word "header" means, as commonly understood in England, the short exposed face, and the long exposed face is likewise termed "stretcher." Moreover, different courses laid alternately as headers and stretchers, may have the two lines of bricks of the stretcher course laid so that each pair of stretcher bricks comes exactly over a pair of header bricks of the next course.

By this means a symmetrical wall of great strength can be built, it being possible to achieve the equivalent strength of a 9 inch thick wall built of ordinary bricks, with an actual perpendicular thickness of less than 9 inches; or greater strength than the ordinary 9 inch brick wall with an actual perpendicular thickness of 9 inches. The length of the short sides of the brick will approximate to that of the short sides of an ordinary brick, i. e. about $4\frac{1}{2}$ inches.

The invention will be further described with reference to the accompanying drawing, wherein:

Figure 1 illustrates two of the improved rhomboidal bricks laid side by side as headers to

show how the construction of each brick is arrived at;

Figure 2 is a section on the line II—II of Figure 1;

Figure 3 is a face view of bricks in two courses of a wall where the courses are laid alternately as headers and stretchers;

Figure 4 is a plan view of two closure bricks which are adapted for interfitment with the improved rhomboidal bricks; and

Figure 5 is a plan view of the corner of two walls meeting at right angles and incorporating rhomboidal bricks of this invention, the corner being finished by an alternative form of closure brick as shown.

In Figure 1 two identical bricks 1 and 2 are shown laid side by side with a predetermined bonding thickness B on the face of the wall. The short sides of the bricks are designated S ,

20 the long sides L , and the acute angle between the sides is α . For a given bonding thickness B and a given length of short side S , the length of the long side L and the angle α is obtained by the expression hereinbefore referred to. When 25 laid as shown in Figure 1, the bricks will have the corners C_2 and C_3 of brick 1 on one face of the wall, and these corners will be disposed perpendicularly opposite the corners C_1 and C_4 of the brick 2 on the opposite face of the wall. 30 The two bricks will thus form a perfect rhomb of equal length sides, and bricks 3 of the next course laid as stretchers (as shown by the chain dot lines) with the predetermined bonding thickness between, will coincide therewith.

35 Where considerable strength is required, or substantial concealment of vertical joints, one or each long side of the improved brick is formed with a recess 4. Two bricks may then be laid side by side in contiguous relationship so that 40 practically no bonding thickness appears on the outer faces of the wall. The term B in the expression aforesaid is thus eliminated or will be very small, and the bricks may be designed on this basis. For continuous uninterrupted walls, 45 such as railway station platforms, sea walls, retaining walls, the improved brick can be used and the vertical joints in one course need bear no relation to the vertical joints of the other courses, since the bond is automatic, and the joints being so thin will hardly be noticed.

Bricks with recesses 4 as just set forth enable reinforcing rods 5 to be incorporated in a wall, the rods passing vertically through the passages formed by the coinciding recesses of the superposed courses. It will be noted that coincident

recesses are obtainable because the bricks in adjacent courses can be laid diagonally in opposite directions to provide a diagonal bond as is usual with rhomboidal bricks. Greater room is provided for the reinforcing rods, when the bricks are laid with the recesses 4 of each pair in a course together, as shown in Figures 1, 2 and 3. Whether or not the reinforcing rods are used, such recesses 4 provide for continuous and substantial columns of bonding vertically through the wall, as will be readily understood from the drawing.

For the purposes of finishing off a wall or joining two walls together at right angles, two forms of closure bricks are provided, as shown in Figures 4 and 5 respectively. One form of closure brick 6, Figure 4, has the shape of a triangle of which the angle made between each inclined side IS and each base side BS of the triangle is equal to the angle α , and the lengths of the sides are such that when two of these triangular bricks are placed with two inclined sides IS adjacent but spaced by the given bonding thickness B—measured parallel to the wall faces—a true rhomb is formed corresponding to the rhomb obtained by placing two rhomboidal bricks together as aforesaid. Thus BS is equal to the length of the long sides L of the rhomboidal bricks.

The second form of closure brick 7, Figure 5, comes at the end of the wall and forms a right angle corner to the wall. It is quadrilateral in shape. Where it is intended to complete the wall, it will have three sides at right angles and the fourth side inclined to correspond with the inclination of the long sides of the rhomboidal bricks, i. e. it will make an angle α with one of its right angle sides. Where two outer walls are to be joined together at right angles, as shown, this corner closure brick will have two sides at right angles, one CS' being of a length equal to the perpendicular distance D between the short sides S of the rhomboidal brick herein defined, and the other CS² being shorter and equal in length to (D—S—B) where S is the length of the short side of the rhomboidal brick and B is the given thickness of bonding, as aforesaid. The other two sides of this corner brick are at right angles to each other, but incline, the one at an angle α to the long side, and the other at an angle (180° — α) to the short side.

The inclined sides of these closure bricks may

be recessed to provide for concealment of the bonding and the housing of reinforcing rods as previously described.

Where the bonding or joint is not to be concealed, its thickness on the face of the wall will be preferably a quarter of an inch, i. e. $B = \frac{1}{4}$ ". If the bricks are formed with recesses as before described, and the bricks are designed for laying with a predetermined bonding thickness between them, these recesses will, in addition to providing room for reinforcing rods, enable a keyed bonding to be obtained between bricks, thereby to increase the strength of the joint.

The improved rhomboidal bricks may be laid as "headers" with their ends or short sides on the face of the work, the bricks of alternate courses being oppositely inclined so that each brick of one course is bonded on the top of a plurality of bricks of the lower course.

Various other forms of laying the bricks may be adopted introducing "stretchers," i. e. where a long side of the brick is exposed on the face of the work, the improved rhomboidal bricks, together with their closure bricks as before described, enabling most requirements in the design of walls to be dealt with economically and in a practical manner, with simplicity in laying and neatness in finishing.

All bricks as herein described will be provided with the usual "frogs" 8 on their opposite flat faces to accommodate bonding between courses of the bricks.

I claim:

A wall comprising bricks of rhomboidal shape in plan, each brick having parallel side faces and parallel end faces extending from side to side of the brick and diagonally relative to said side faces, at least one side face of each brick having a recess therein spaced inwardly at its ends from the ends of the brick, said bricks being laid in superimposed courses, the bricks in certain of the courses extending parallel to the wall and the bricks in other courses extending transversely of the wall, the recesses of superimposed bricks of the different courses having the medial portions of their recesses vertically aligned, vertical reinforcing rods disposed in the aligned medial portions of the recesses of superimposed bricks, and bonding material in said recesses.

WILLIAM STANLEY GRICE.
